CHEST OF DRAWERS

Ernest Herrmann, Westport, Conn., assignor to Heywood-Wakefield Company, Gardner, Mass., a corporation of Massachusetts

Application August 8, 1958, Serial No. 52,140

Term of patent 7 years

(Cl. D33—6)

Fig. 1 is a front view of a chest of drawers showing my new design;

Fig. 2 is a fragmentary sectional view on the line 2—2 of Fig. 1, but on a larger scale; and

Fig. 3 is a fragmentary view on the line 3—3 of Fig. 1, but on a larger scale.

The back and sides of the chest are plain and of conventional configuration.

The dominant features of the design are the parts shown in full lines.

I claim:

The ornamental design for a chest of drawers, substantially as shown and described.
